MACHINE FOR MAKING SPIRALS

William F. H. Braun, Wynnewood, Pa.

Application July 21, 1944, Serial No. 545,995

3 Claims. (Cl. 153—54)

1

The principal object of the present invention is to provide a simple, reliable and efficient machine for making spirals, for example cutters, for lawn mowers and for other purposes.

Other objects of the invention will appear from the following description at the end of which the invention will be claimed.

In the following description, reference will be made to the accompanying drawings forming part hereof and in which:

Fig. 1 is a side view partly in section of a machine embodying features of the invention;

Fig. 2 is a top or plan view of the same;

Fig. 3 is a side elevational view drawn to a reduced scale and looking from the top of the sheet toward the bottom in Fig. 2;

Fig. 4 is a face view of a strip of metal or blade to be bent into spiral form;

Fig. 5 is a view of the same bent into curved form;

Fig. 6 is a view of the strip shown in Fig. 5 twisted into spiral form;

Fig. 7 is a transverse sectional view of the strip shown in Fig. 4;

Fig. 8 is a sectional view taken on the line 8—8 of Fig. 1 and showing the feed rolls;

Fig. 9 is an end view showing the twisting rolls;

Fig. 10 is a detached elevational view of the die;

Fig. 11 is a view of the left-hand end of the die shown in Fig. 10;

Fig. 12 is a view of the right-hand end of the die shown in Fig. 10; and

Fig. 13 is a view of one-half of the die shown in Fig. 10.

Referring to the drawings, the invention will be described in connection with the manufacture of spiral blades for lawn mowers but the machine of the invention is applicable to other uses and purposes. 1 indicates a frame or housing. Mounted on one face of the frame or housing are sizing and feed rolls 2. These rolls are of substantially the same diameter and are grooved and journaled to the exact dimensions of the finished blade or strip and they are positively driven by means of the gear wheels 3. 4, 5 and 6 are bending rolls of which roll 4 is driven by gear wheel 7. The roll 4 is of larger diameter than the rolls 5 and 6 which are of the same diameter. The rolls 5 and 6 are spaced apart and are shown as peripherally grooved. The roll 6 is also shown as peripherally grooved. 8 is a drive shaft for driving the various gears which are arranged on the other face of the housing. 9 is a die shown

2

as detachably connected with the housing 1 so that different dies may be employed. The cavity through the die is of twisted form as illustrated in Figs. 10 to 13.

At the entrance of the die are two pairs of co-operating cylindrical rolls 10 and 11 of which one pair is shown in Fig. 9. In Fig. 1, the rolls 10 are mounted in a plate 12 (Fig. 9) and the rolls 11 are mounted in a similar plate and are set at an angle in respect to the rolls 10 as indicated by the dot-and-dash line in Fig. 9. The die (Fig. 2) and the plates which carry the rolls 10 and 11 are mounted in a sleeve detachably arranged in the die holder. The bite between the rolls 10 is aligned with the entrance to the cavity in the die.

The mode of operation of the machine may be described as follows. A straight strip of metal *a* as shown in Figs. 4 and 7 is fed to the machine and, in passing between the grooved sizing and feed rolls 2, any slight irregularity in dimension is corrected and the strip is fed forward. In passing between the bending rolls 4, 5 and 6, the strip is bent into curved form as shown in Fig. 5. In passing through the twisting rolls 10 and 11, the strip assumes spiral form as shown in Fig. 6; and, in passing through the die, any irregularity in the spiral form of the strip is corrected.

It will, of course, be understood that the strip 30 may be fed to the machine in sections and each following section pushes the section ahead of it through the machine.

It will be obvious to those skilled in the art that modifications may be made in details of construction and arrangement and procedure without departing from the spirit of the invention which is not limited as to such matters or otherwise than the appended claims may require.

I claim:

1. In a machine of the type recited, the combination of, a pair of peripherally grooved sizing and feeding rolls, a set of three bending rolls, two pairs of twisting rolls of which the axes are inclined in respect to the axes of the other rolls, a spiral die arranged in progression, and means for driving the sizing and feeding rolls.

2. In a machine of the type recited, the combination of, a pair of feed rolls, a set of three bending rolls of which two are of substantially the same diameter and the third is of greater diameter, two pairs of twisting rolls of which the axes are inclined in respect to the axes of the other dies, a spiral die, and means for driving each of the feed rolls and for driving the bending roll of largest diameter.

3. In a machine of the type recited, the combination of, a housing, a pair of peripherally grooved feed rolls, a set of three bending rolls of which one is of larger diameter than the other, two pairs of twisting rolls of which the axes are inclined in respect to the axes of the other rolls, all of said rolls arranged at one face of

the housing, a spiral die detachably connected with one end of the housing and aligned with said rolls, and means arranged on the other face of the housing for driving each pair of feed rolls and for driving the bending roll of largest diameter.

WILLIAM F. H. BRAUN.
